UNITED STATES PATENT OFFICE.

MARGUERITE HUGHES, OF JOHNSON CITY, TENNESSEE.

DESIGN FOR A DOLL STATUETTE.

Application filed March 10, 1924. Serial No. 8,895. Term of patent 3½ years.

To all whom it may concern:

Be it known that I, MARGUERITE HUGHES, a citizen of the United States, residing at Johnson City, in the county of Washington and State of Tennessee, have invented a new, original, and ornamental Design for a Doll Statuette, of which the following is a specification, reference being had to the accompanying drawing, forming part thereof.

I claim:

The ornamental design for a doll statuette, as shown.

MARGUERITE HUGHES.
